SUPERHEATER UNIT

Walter H. Hinsch, Chicago, Ill.

Application May 9, 1935, Serial No. 20,546

9 Claims. (Cl. 122—462)

This invention relates to improvements in superheater units and it consists of the matters hereinafter described and more particularly pointed out in the appended claims.

One of the objects of the invention is to provide a superheater unit especially adapted for use in locomotives and wherein heat units are transferred to the incoming saturated steam instead of to the outgoing flue gases so that an equalizing action on the thermal loading is afforded and no loss in thermal heat results.

Another object of the invention is to provide a superheater unit wherein the superheated steam is employed initially to raise the temperature or superheat of the incoming saturated steam so that it is in better condition for final superheating in its passage through the final steam superheating tube of the unit.

A further object of the invention is to provide a superheater unit which may be readily substituted for those recognized as standard and now in use and when so substituted will raise the operating efficiency of the locomotive.

Still a further object of the invention is to provide a superheater unit which is practical to make and install and which is more efficient in operation than other units now used for the same purpose.

In the drawing:

Fig. 1 is a longitudinal horizontal sectional view through a locomotive flue containing a superheater unit embodying the preferred form of the invention;

Fig. 2 is a longitudinal vertical sectional view through the locomotive flue, as taken on the line 2—2 of Fig. 1 and illustrates the improved superheater unit in side elevation; and

Figs. 3, 4 and 5 are transverse vertical detail sectional views on a somewhat enlarged scale as taken on the line 3—3, 4—4 and 5—5, respectively, of Fig. 2.

In general, the improved unit includes a saturated steam receiving tube at the front end through which extends an outgoing superheated steam tube so as to be surrounded by the incoming saturated steam in the first mentioned tube and which saturated steam receives heat units for initial superheating before it receives its final superheating in the tubes provided therefor. In this manner, there is no heat loss to the gases in the front end of the flue though there may be a heat transfer from the outgoing superheated steam to the incoming saturated steam.

Referring now in detail to that embodiment of

the invention, illustrated in the accompanying drawing—

1 indicates one of the flues of a locomotive boiler secured at its ends in the conventional manner in the front and rear flue sheets 2 and 3 respectively. 4 indicates, as a whole, the improved superheater unit arranged in said flue. The improved unit includes an incoming saturated steam tube 5 at the front end of the flue and which tube, as herein shown, is of a cruciform or clover-leaf cross section of such diameter as to leave a gas passage space 6 between said tube and the flue 1. The tube 5 is provided with radial spacers or supports 7 to keep it properly positioned within the flue. At the ends of 10 the tube 5 are front and rear closure heads 8 and 9 respectively, each having a pair of top and bottom, outwardly extending flanges or collars 10—11 and 12—13 respectively.

Within the incoming saturated steam receiving tube 5 is an outgoing superheated steam tube, the intermediate portion 14 of which is disposed in the axis of the tube 5 and the ends of which, are offset upwardly to be secured in the top collars or flanges 10 and 11 of the end heads 8 and 9. The collar 11 has secured thereto a saturated steam inlet tube 15 leading from the saturated steam compartment of a superheater header not shown. The collar 10 also has secured thereto a superheated steam outlet tube 16 leading to the superheated steam compartment of the header before mentioned.

In the flue 1, rearwardly of the incoming saturated steam tube 5, is the final steam superheating arrangement for the unit. This arrangement, as shown herein, is of the so-called double loop tube form and includes four tube sections 17, 18, 19 and 20 respectively. The front end of the tube section 17 is secured in the bottom collar or flange 13 of the tube 5 and receives initially 35 superheated steam from the rear end of said incoming saturated steam tube 5. The rear end of the tube section 17 is connected by a bend with the rear end of the tube section 18, the front end of the last mentioned tube section being connected by a bend with the front end of the tube section 19. The rear end of the tube section 19 is connected by a bend with the rear end of the tube section 20, the front end of which connects with the inlet end of the outgoing superheated 40 steam tube 14. Thus the steam in the tube sections 17, 18, 19 and 20 is caused to take a tortuous path with resulting counter-flows.

The group of tube sections 17, 18, 19 and 20, which are disposed in the rear end of the flue 55

where the highest temperature prevails, are held in grouped relation by means of a spacer and surrounding band 21-22, the latter including spacer or supports 23 as best shown in Fig. 3 for holding the said tube sections centrally in the flue 1.

In operation, saturated steam enters the tube 5 from the tube 15 and fills said tube 5 and surrounds the tube 14 therein. In the passage or flow of the saturated steam through the tube 5 from the front to its rear end, said saturated steam absorbs heat units from the outgoing superheated steam in the tube 14 and is initially superheated thereby. As the tube sections 17, 18, 19 and 20 are disposed in the hottest end of the flue 1, the steam passing therethrough picks up the heat units from the hot gases to become superheated. The superheated steam then passes through the tube 14 and out of the same through the tube 16 to the superheated steam compartment of the superheater header, not shown. As the outgoing superheated steam passing through the tube 14 has a much higher temperature than the incoming saturated steam in the tube 5, the saturated steam will absorb heat units therefrom. This heat unit transfer, however, cannot be reckoned as a superheat loss because it is employed as the initial superheat for the saturated steam which, in turn acts as a heat insulator between the superheated steam and the low temperature gases passing out through the front end of the flue. Thus when the superheated steam is entirely surrounded by the saturated steam, this avoids reheating the flue gases at this point with a resulting loss. Therefore the transfer of heat units from the tube to the saturated steam does not result in a heat loss but exerts only an equalizing effect on the thermal loading.

By the use of the saturated steam tube of cruciform or clover-leaf cross section, the area of each end becomes large enough to receive the associated pair of tubes and at the same time, the superficial area of the tube 5 is increased without unduly sacrificing gas passage space at this point.

It is apparent that instead of the double loop or four section tubes herein shown and described, a tube of the so-called single loop or "hairpin" type may be employed without departing from the spirit of the invention.

Preferably in making up the tube 5, the heads 8 and 9 are made separately and then welded in place.

The construction described does not require special fittings or alterations to make it possible for substitution in making replacements. The improved construction is simple and efficient and can be made in accordance with present boiler practice.

While in describing the invention, I have referred in detail to the form, arrangement and construction of the various parts thereof, the same is to be considered only in the illustrative sense so that I do not wish to be limited thereto except as may be specifically set forth in the appended claims.

I claim as my invention—

1. A superheater unit embodying therein an incoming saturated steam tube, an outgoing superheated steam tube having a major portion between its ends arranged within the first mentioned tube so as to be surrounded by the saturated steam therein for a direct exchange of

heat between the outgoing superheated steam and the incoming saturated steam, and a steam superheating arrangement communicating at its front end with the rear ends of the incoming saturated steam receiving tube and the outgoing superheated steam tube.

2. A superheater unit embodying therein an incoming saturated steam receiving tube, an outgoing superheated steam tube arranged axially of and extending the full length of said incoming saturated steam tube so as to be surrounded by the steam therein for a direct exchange of heat between the outgoing superheated steam and the incoming saturated steam, and a steam superheating arrangement communicating at its front end with the rear ends of the incoming saturated steam tube and the outgoing superheated steam tube.

3. A superheater unit embodying therein an incoming saturated steam tube, an outgoing superheated steam tube having its full length portion arranged within the first mentioned tube so as to be surrounded by the saturated steam therein for a direct exchange of heat between the outgoing superheated steam and incoming saturated steam, and a steam superheating arrangement connected at its front end to the rear ends of the incoming saturated steam tube and the outgoing superheated steam tube, the superheated steam in the outgoing superheated steam tube having a flow counter to the incoming saturated steam in the saturated steam tube.

4. A superheater unit embodying therein an incoming saturated steam tube, an outgoing superheated steam tube extending longitudinally through the incoming saturated steam tube so as to be surrounded by the saturated steam therein for a direct exchange of heat between the outgoing superheated steam and the incoming saturated steam, and a loop-like steam superheating tube connected at its front ends to the rear ends of the incoming saturated steam receiving tube and the outgoing superheated steam tube.

5. A superheater unit embodying therein an incoming saturated steam tube closed at both ends and having a pair of tube connections at each end, a saturated steam inlet and a superheated steam outlet engaged in a pair of connections at one end of the tube, a steam superheating tube of loop formation having inlet and outlet ends engaged in a pair of connections at the other end of the incoming saturated steam tube, and an outgoing superheated steam tube in the saturated steam tube so as to be surrounded by the steam therein and engaged at its ends in said connections in which the superheated steam outlet and the outlet end of said loop formation are engaged.

6. A superheater unit embodying therein an incoming saturated steam tube of cruciform cross section and having a head at each end, an outgoing superheated steam tube arranged with the greater portion of its length axially in the incoming saturated steam tube so as to be surrounded by the saturated steam therein for a direct exchange of heat thereto, the ends of said outgoing superheated steam tube being offset and engaged in the heads of said saturated steam tube, and a steam superheating tube arrangement communicating at its front end with the rear ends of the incoming saturated steam receiving tube and the outgoing superheated steam tube.

7. In combination with a boiler flue, means providing an incoming saturated steam tube in

the front end of said flue and separated therefrom by an annular flue gas passage, an outgoing superheated steam tube having its full length arranged within the first mentioned tube so as to be surrounded by the saturated steam therein for a direct heat exchange thereto, a saturated steam inlet for said incoming saturated steam tube, and a superheated steam outlet communicating with the front end of the incoming saturated steam tube and the outgoing superheated initial steam tube respectively, and a steam superheating tube of loop formation arranged in said flue rearwardly of said incoming saturated steam tube and communicating at its front ends with the rear ends of the saturated steam tube and the outgoing superheated steam tube.

8. In combination with a boiler flue, means providing an incoming saturated steam tube of cruciform cross section in the front end of said flue and separated therefrom to be surrounded by a gas passage therein, an outgoing superheated steam tube having its greatest length disposed centrally in said incoming saturated steam tube so as to be surrounded by the saturated steam therein for a direct heat exchange thereto, said outgoing saturated steam tube having its ends fixed off-center in the ends of said saturated

steam receiving tube, a saturated steam inlet and a superheated steam outlet communicating with one end of said incoming saturated steam tube and with one end of said outgoing superheated steam tube respectively, and a steam superheating tube of loop formation arranged in said flue rearwardly of said incoming saturated steam tube and communicating at its front ends with the rear end of the incoming saturated steam tube and with the outgoing superheated steam tube. 5 10

9. In a superheater unit, means providing a tubular body, a head closing each end of said body and each head having a plurality of openings therein offset with respect to the axis of said body, a tube in said body having a mid portion thereof arranged substantially axially of the body and having end portions offset axially of the body and each end portion being connected in at least one opening in each head, one end of said tube in one head serving as a superheated steam outlet and the opening in the same head serving as a saturated steam inlet for said body, and a conduit member connecting the opening in the other head with the end of the tube connected 15 20 25 in the same head.
